(57) **CLAIM**

The ornamental design for a case for a computing device, as
shown and described.

DESCRIPTION

FIG. 1 is a front perspective view of the case for a computing device;

FIG. 2 is a back perspective view of the case for a computing device shown in FIG. 1;

FIG. 3 is a front plan view of the case for a computing device shown in FIG. 1;

FIG. 4 is a back plan view of the case for a computing device as shown in FIG. 1;

FIG. 5 is a side view of the case for a computing device as shown in FIG. 1;

FIG. 6 is a left side view of the case for a computing device as shown in FIG. 1;

FIG. 7 is a top view of the case for a computing device as shown in FIG. 1; and,

FIG. 8 is a bottom view of the case for a computing device as shown in FIG. 1.

The features shown in broken lines, and any surfaces of the
design not shown, including interior surfaces, form no part
of the claimed design.
